Attorney

UNITED STATES PATENT OFFICE.

WALTER E. DENTTEN, OF MILWAUKEE, WISCONSIN.

SHOE LAST.

Application filed March 4, 1922. Serial No. 541,189.

To all whom it may concern:

Be it known that I, WALTER E. DENTTEN, a citizen of the United States of America, residing at Milwaukee, in the county of Milwaukee and State of Wisconsin, have invented certain new and useful Improvements in Shoe Lasts; and I do hereby declare that the following is a full, clear, concise, and exact description of the invention, such as 10 will enable others skilled in the art to which it appertains to make and use the same.

This invention relates to improvements in shoe lasts, having for an object to provide an attachment for shoe lasts whereby the 15 rearward or that portion of a shoe upper adjacent the heel piece will be firmly connected to the heel portion of the last upon arrangement of such upper thereon, thus retaining the upper in fixed position upon 20 the last during work thereupon.

It is well known in the art that in arranging shoe uppers upon lasts, preparatory to assembly, it is necessary that the worker drive a tack through that portion of the 25 upper adjacent its heel piece into the last in order that displacement or undue movement of the upper with relation to the last will be prevented. When the work upon the upper is complete, this tack is removed, but there 30 remains in the shoe upper the hole made by the same. In my invention, means are provided for releasably anchoring the upper to the shoe last without the necessity of marking the former as by driving tacks there- 35 through.

Other objects of the invention will be in part obvious and in part pointed out herein-after.

In order that the invention and its mode 40 of operation may be readily understood by persons skilled in the art, I have in the accompanying illustrative drawings and in the detailed following description based thereon, set out one possible embodiment of 45 the same.

In these drawings:

Figure 1 is a side elevation of the improved last, a part thereof being broken away and shown in section;

Figure 2 is a side elevation of a last fitted with the improved attachment, the last being in its open position;

Figure 3 is a rear elevation of the last;

Figure 4 is a fragmentary perspective 55 view showing the relation of the forward end of the catch in the heel section of the

last with relation to the inner end of the toe section thereof; and,

Figure 5 is a detail in elevation of the type of catch employed together with the 60 spring means for normally retaining the same in its distended position.

Having more particular reference to the drawings, in connection with which like characters of reference will designate corresponding parts throughout, I have illustrated for the purpose of convenience, the invention as applied to that type of last including hingedly connected toe and heel sections 1 and 2 respectively, the hinged connection being effected as indicated at 3, while the inner end of the heel section 2 is provided with a cut away portion which with closing of the last receives an extension or projecting portion arranged upon the inner end of the toe section 1, as clearly shown in the Figure 1.

A longitudinal way is formed in the lower portion of the heel portion 2 and as will be noted, has arranged between the forward or inner ends of the same, a second way or seat indicated for the purpose of convenience by the numeral 4.

Slidably received in the longitudinal way in the lower portion of the heel section 2 are 85 the opposite side or leg portions of a substantially U-shaped catch 5, it being noted that the basal portion of said catch is curved upon itself and normally extended from the inner end of the heel section 2, whereby it 90 may be engaged by the inner end of the projecting portion arranged or carried upon the inner end of the toe section 1 in the manner as illustrated in the Figures 2 and 4. In order that the basal portion of the U-shaped 95 catch 5 will be normally arranged in its distended position with relation to the inner end of the heel section 2, I may and preferably do provide in the enlarged pocket 4 between and communicating with the way 100 receiving the opposite sides of said catch, an expansible coiled spring 6, one end of said spring bearing upon the rearward wall of the pocket 4 while the opposite end portion of the same is engaged over a boss 7 arranged intermediately of and upon the inner side of the basal portion of the catch 5 as shown in the Figure 5. Because of this 105 positioning of the expansible coiled spring 6, it will be readily understood that an inward thrust will be normally imparted to the catch 5 and in consequence, that the

curved basal portion thereof will be normally maintained in distended position with relation to the inner end of the heel section 2. Hence, when the last is in open position 5 as indicated in the Figure 2, the free extremities of the U-shaped catch 5 will be in their retracted positions as shown in dotted lines, the inner or basal portion of said catch being arranged directly adjacent the 10 projecting portion upon the inner end of the toe portion 1 of the last construction.

However, when the toe portion 1 is swung downwardly upon its hinged connection to the position as shown in the Figure 1, the 15 projecting portion upon its inner end will engage and impart an outward thrust to the basal portion of the U-shaped catch 5, thus moving the free ends of said catch to positions whereat they will be extended 20 from the adjacent outer end portion of the heel section 2 as also shown in the Figure 1. Because of the interpositioning of the 25 expandible coiled spring 6, although, it will be understood that with swinging of the toe section 1 to its open or uppermost position, the free extremities of the U-shaped catch 5 will be immediately retracted and the basal portion thereof moved to distended 30 position as shown in the Figure 2 with relation to the inner end of said heel section 2.

In using the improved last, an upper is arranged over the toe and heel sections 1 and 2 thereof, whereupon said sections will be moved to their closed positions as shown 35 in the Figure 1. With closing of the shoe last sections, the projecting portion upon the inner end of the toe section 1 will impart an outward thrust to the spring pressed U-shaped catch 5, thus causing the free or 40 outer ends of said catch to be moved outwardly from the outer end portions of the heel section 2 into engagement with those portions of the shoe upper in proximity to the heel seat of the same. By reason of the 45 engagement of the free ends of the U-shaped catch 5 with the heel portion of the upper arranged upon the last, it will be understood that the same will be firmly anchored in its position upon the last and will be 50 prevented from having undue shifting movement or displacement during work thereupon. When work upon the upper is completed, the same may be then moved from the last and the sections permitted to 55 move to their relatively open positions, whereupon the free ends of the U-shaped catch 5 will be immediately moved to their retracted positions. Because of the blunt formation of the free ends of the catch 5, it 60 will be understood that marking or mutilating of the shoe upper will have been prevented and yet, the same will have been afforded a positive means for anchoring it in

position upon the shoe last during work thereon.

Manifestly, the construction shown is capable of considerable modification and such modification as is within the scope of my claims, I consider within the spirit of my invention.

I claim:

1. In combination with a shoe last including relatively adjustable toe and heel sections, the heel section having a longitudinal way formed in its lower portion, and a catch of a length greater than the heel section slidable in said way having its inner end normally extended beyond the inner end of the heel section adapted to have abutting engagement with an adjacent portion 75 of the toe section, as and for the purpose set forth.

2. In combination with a shoe last including relatively adjustable toe and heel sections; the heel section having a longitudinal way formed in its lower portion, a catch 85 slidable in said way being of a length greater than the length of the heel section and having its inner end normally extended beyond the inner end of the heel section 90 adapted to have abutting engagement with an adjacent portion of the toe section, and spring means connected to the inner end of said catch for removably retaining said inner end in extended position.

3. In combination with a shoe last including relatively adjustable toe and heel sections, the heel section having a longitudinal way formed in its lower portion and a substantially U-shaped catch of a length 100 greater than the length of the heel piece having the opposite side thereof slidably in said way and its inner basal portion normally extended beyond the inner end of the heel piece adapted to have abutting engagement with an adjacent portion of the toe section, as and for the purpose set forth.

4. In combination with a shoe last including hingedly connecting toe and heel sections, said heel section having a longitudinal way formed in its lower portion, a substantially U-shaped catch of a length 110 greater than the length of the heel section having its opposite side portions freely slid 115 able in said longitudinal ways, the inner or basal portion of said U-shaped catch being normally extended beyond the inner end of the heel section and adapted to be abuttingly engaged by an adjacent portion of the inner end of said toe section, and spring 120 means for normally retaining said basal portion in its extended position.

In witness whereof I have hereunto set my hand.

WALTER E. DENTEN.
